UNITED STATES PATENT OFFICE.

OTTO A. HOKANSON, OF WOODSTOCK, ILLINOIS, ASSIGNEE TO WOODSTOCK TYPEWRITER COMPANY, OF WOODSTOCK, ILLINOIS, A CORPORATION OF ILLINOIS.

RIBBON-SPOOL HOLDER FOR TYPEWRITERS.

Application filed May 17, 1920. Serial No. 381,822.

To all whom it may concern:

Be it known that I, OTTO A. HOKANSON, a citizen of the United States, residing at Woodstock, in the county of McHenry and State of Illinois, have invented certain new and useful Improvements in Ribbon-Spool Holders for Typewriters, of which the following is a specification.

This invention has for its object the provision of a device of the character named which shall be of improved construction and operation.

The invention is exemplified in the combination and arrangement of parts shown in the accompanying drawings and described in the following specification, and it is more particularly pointed out in the appended claims.

In the drawings—

Fig. 1 is a top plan view of a ribbon spool holder embodying one form of the present invention;

Fig. 2 is a vertical section substantially on line 2—2 of Fig. 1;

Fig. 3 is a fragmentary elevation looking from the right in Fig. 1;

Fig. 4 is a vertical sectional view of a slightly modified form of the invention; and

Fig. 5 is a horizontal section on line 5—5 of Fig. 4.

Referring first to Figs. 1, 2 and 3, the numeral 10 designates an upright spindle for receiving a ribbon spool 11, the spindle 10 being rotatable in any well-known manner for winding the ribbon upon the spool. Mechanism not shown is provided for reversing the direction of rotation of the spindle 10, and this mechanism is controlled by a rod 12 extending downwardly through an opening in the spindle 10. The rod 12 is bent laterally and provided with a pin 13 projecting through a slot in the side of the spindle 10. The spindle 10 carries a collar 14 fixed to the spindle and slotted to accommodate the laterally extending pin 13 of the rod 12. A yoke 16 is pivoted at 17 on the sleeve 14 and provided with an upwardly extending finger 18 arranged to project through an opening in the lower flange 19 of the spool 11 and to be folded into a slot formed in the central spool core when a ribbon is wound upon the spool in a manner well known in the art. When the ribbon has been completely unwound from the spool 11 the finger 18 will drop by gravity and swing about its pivotal support 17 permitting the rod 12 to fall and thus shift the direction of movement of the mechanism for rotating the spindle 10. It is understood that the pin 13 extends through an opening 60 in the yoke 16 so that movement of the finger 18 and the yoke 16 about the pivot 17 shifts the rod 12 in the direction of the axis of the spindle 10.

When it becomes desirable for changing 65 the ribbon or other purposes to remove the spool 11 the finger 18 will fall by gravity into the position shown in Fig. 2, and in former devices of this kind it has been necessary to hold the finger 18 in its innermost 70 position when a spool with the ribbon wound thereon is replaced upon the spindle. The present invention includes mechanism for more easily holding the finger 18 in position to receive a spool with the ribbon wound 75 thereon. A casing 20 is supported in any convenient means upon the frame of the typewriter and surrounds the spindle 10 and spool 11. A slot 21 is formed at one side of the casing, as shown most clearly in Fig. 80 3, and a lug 22 is formed on the wall of the casing adjacent the slot 21. A lever 23 is provided with a lug 24 pivotally supported at 25 on the lug 22. A slide 26 is mounted in the slot 21 and provided with guide lugs 85 27 and 28 which are formed on the edges of the casing 20 adjacent the slide. The upper end of the slide 26 is provided with an eye 29 which receives a pivot pin 30 carried by a lug 31 on the lever 23. The lower end of 90 the slide 26 carries an arm 32 which supports a ring 33 surrounding the collar 14 and yoke 16. The ring 33 lies just below the projecting end of the pin 13. The free end of the lever 23 is perforated to receive 95 the upper end of the spindle 10 and is provided with a finger-piece 34 by which the lever may be swung upwardly about its pivot 25. Before the spool 11 can be removed from the spindle 10 it is necessary to 100 raise the lever 23 to leave the upper end of the spindle free. As the lever is lifted it raises the slide 26 and the ring 33 so that the ring engages the pin 13 moving the pin upwardly and swinging the finger 18 into its 105 closed position. The upward movement of the lever 23 will swing the pin 30 about the pivot 25 so that the pin 30 moves to the right, as viewed in Fig. 2, in addition to its upward movement. This lateral movement 110

is permitted by the fact that only two sets of guides 27 and 28 are employed and by the fact that the slide 26 is free to move past the end of the pivot 25 since the pivot 25 is located entirely at one side of the slot 21. If the lever 23 is swung far enough the pin 30 will move outwardly past the vertical plane of the pivot 25 so that the lever 23 will be held open by the weight of the slide 26 and the arm 32. As long as the lever remains in its open position the finger 18 will be held retracted so that the ribbon spools can be replaced without interfering with the control finger 18. If the lever 23 is swung to its closed position it will prevent the placing of a spool upon the spindle 10 so that whenever the lever is in position to permit a spool to be placed upon the spindle the finger 18 will be folded inwardly so that it will not interfere with the movement of the spools into place. The spools 11 are provided with pins 35 which project into slots 36 in the collars 14 to cause the spools to rotate with the spindle 10.

25 The form of the invention shown in Figs. 4 and 5 is quite similar to that of Figs. 1, 2 and 3, with the exception that the slide 26 carries an arm 37 extending substantially horizontal and surrounding the spindle 10 above the pin 13 instead of below, as in the previous case. With this form of invention, raising the lever 23 causes the ring 38 carried by the arm 37 to bear against the finger 18 and force it inwardly instead of bearing against the pin 13, as is done in the device previously described. At the same time the edge of the ring 38 engages the lower flange of the spool and partially lifts the spool so that it may be readily grasped for removal.

40 I claim:—

1. In a typewriter, a ribbon spool support, a control device connected with said support and movable into and out of position for permitting a spool to be placed on said support, and means for intercepting the movement of a ribbon spool into position on said support prior to its engagement with said control device when said control device is improperly positioned to receive said spool.
2. In a typewriter, a ribbon spool support, a device for controlling the direction of rotation of a spool on said support, means for holding said device in position to permit passing of a spool onto said support, and means for intercepting the movement of a spool onto said support while said controlling device is out of proper position for receiving said spool.
3. In a typewriter, a ribbon spool support, a member movably mounted on said support for controlling the operation of a spool on said support, a device for holding said member in position for receiving a spool onto said support, and means for ac-

tuating said holding device to move said member into receiving position, said actuating means being arranged to intercept the movement of a spool onto said support when said control member is out of position for receiving a spool onto said support. 70

4. In a typewriter, a detachable ribbon carrier, a device controlled by the ribbon on said carrier for governing the operation of said carrier, a device movable into and out of position to permit detachment of said carrier, and means controlled by said second-mentioned device for assuming control of said ribbon controlled device when said second-mentioned device is in position to 80 permit detachment of said carrier. 75

5. In a typewriter, a detachable ribbon carrier, means controlled by the ribbon on said carrier for governing the movement of said carrier, and mechanism for controlling 85 the movement of said carrier onto and off of said typewriter and for shifting the position of said governing means to prevent its interfering with the movement of said carrier onto and off of said typewriter. 90

6. In a typewriter, a detachable ribbon carrier, a device controlled by the ribbon on said carrier for governing the operation of said carrier, means movable into and out of position for intercepting the movement of said carrier into and out of operating position on said typewriter, and means connected with said intercepting means for shifting the position of said governing device to hold said governing device in position to receive 100 said carrier when said intercepting means is in position to permit said carrier to be placed on said typewriter. 95

7. In a typewriter, a ribbon spool support, ribbon actuating mechanism, a control 105 device for said mechanism mounted on said support and movable into extended and retracted positions, and manually operated means for shifting said control device.

8. In a typewriter, a ribbon spool support, a device mounted on said support for controlling the direction of movement of a ribbon spool thereon, and manually operated means for shifting said device into position to permit a ribbon spool to be placed upon 115 said support.

9. In a typewriter, a ribbon spool support, a device for controlling the direction of rotation of a ribbon spool on said support, said device being movable into and out 120 of position to permit a ribbon spool to be placed upon said support, and manually operated means for shifting said device, said operating means being arranged when in one position to extend into the path of a ribbon 125 spool as it is moved onto and off of said support.

10. In a typewriter, a ribbon spool support, a ribbon control finger for governing the direction of rotation of the spool on said 130

support, a device for shifting the position of said finger, and means connected with said device for controlling the movement of a spool onto and off of said support, said means being arranged to intercept the movement of a spool onto said support when said finger is improperly positioned for receiving a spool.

11. In a typewriter, a ribbon spool support, ribbon control means for governing the operation of a spool on said support, and a lever for shifting the position of said ribbon control means, said lever being movable into and out of the path of a spool as it moves onto and off of said support.

12. In a typewriter, a ribbon spool support, a ribbon control finger mounted on said support, a device for shifting said finger into and out of position to receive a spool on said support, and a lever for actuating said finger shifting means, said lever being movable into one position to extend into the path of said spool moving onto and off of said support.

13. In a typewriter, a ribbon spool sup-

port, a device for controlling the operation of a spool on said support, and means arranged to be moved out of the path of said spool for moving said spool out of position on said support and shifting said device into position to receive a spool placed upon said support.

14. In a typewriter, a ribbon spool support, a device for controlling the operation of a spool on said support, means for shifting said device, and means for actuating said shifting means, said actuating means being movable into one position to prevent movement of a spool onto and off of said support and into another position to permit movement of a spool onto and off of said support and to hold said control device in a position in which it will not interfere with the movement of a spool onto and off of said support.

In testimony whereof I have signed my name to this specification on this 12th day of May, A. D. 1920.

OTTO A. HOKANSON.
